UNITED STATES PATENT OFFICE.

ARTHUR O'CONNOR, OF WESTGATE, IOWA.

SHELF FOR LADDERS.

1,245,958.

Specification of Letters Patent. Patented Nov. 6, 1917.

Application filed March 29, 1917. Serial No. 158,360.

To all whom it may concern:

Be it known that I, ARTHUR O'CONNOR, a citizen of the United States, residing at Westgate, in the county of Fayette, State of Iowa, have invented a new and useful Shelf for Ladders; and I do hereby declare the following to be a full, clear, and exact description of the invention, such as will enable others skilled in the art to which it applies to make and use the same.

The invention is a shelf for ladders and seeks to provide, as one of its objects, a shelf that can be hung conveniently on the side of a ladder out of the way of the workmen.

A further object is to provide, in such a shelf, means for attaching it at the back of a ladder also.

A still further object is to provide means for rigidly supporting the shelf when it is hung on the back of the ladder.

A still further object is to make the rigid supporting means adjustable, so that the shelf may be maintained in a horizontal position with various angles of inclination of the ladder.

Other objects will appear from the detailed description which follows.

In illustrating this invention, a particular design has been adhered to but the invention is not to be confined to this especial design. The right is reserved to make any changes or alterations compatible with the appended claims.

The same numerals of reference designate the same parts throughout the several figures of the drawings, wherein:

Figure 1 is a perspective view of the invention, showing it on the side of a ladder.

Fig. 2 is a side elevation of a portion of a ladder with the invention affixed to the back thereof.

Fig. 3 is a sectional view, taken back of one of the supports of the shelf, to show clearly the manner in which the shelf is attached to the rungs of the ladder.

Fig. 4 is a section on the line 4—4 of Fig. 1.

The invention is shown attached to a conventional ladder composed of the legs 1 and rungs 2. The invention itself comprises the substantially Z-shaped hangers comprising the upright parts 3, the upper horizontal parts 11, and the lower horizontal parts 8. Secured to the lower horizontal parts is a shelf board 4, and to the upright parts a

back 5 is attached by screws 6. A bracing rod 7 is attached between the upright parts 3, of the hangers and has its ends suitably fixed in said upright parts, and acts as a spacing brace between the two.

The lower horizontal parts 8 of the hangers 3 have enlargements 9 between which a rod 10 is suitably attached and acts as a lower spacing brace.

The upper horizontal parts 11 of the hangers 3 have the depending ends 12 between which and the upper ends of the braces 13 slots 15 are formed to permit the attachment of the hangers to the bar 14. The braces 13 are attached to the upper horizontal parts 11 and to the upright parts 3 of the hangers by suitable rivets or the like 16.

The bar 14, at each end is provided with slots 19 in which the upper horizontal parts 11 engage, the depending ends 12 abutting the bar on one face and the upper ends of the braces 13 abutting this bar on the other face. At its longitudinal center, the bar 14 is provided with a slot 17 for engagement with the rungs 2 of the ladder when the shelf is hung on the side thereof. Between the slot 17 and one end, the bar 14 is provided with a series of depressions 18 which engage the rod 10 when the shelf is attached on the back of the ladder.

When it is desired to hang the shelf on the side of the ladder, it is attached as shown in Fig. 1, the slot 17 of the bar 14 being made to engage one of the rungs 2 of the ladder and the shelf is connected to the bar 14 by having the upper horizontal parts 11 engage the end slots 19 thereof. The shelf is then ready to support a bucket or whatever else it may be desired to place upon it, the shelf and its contents being then conveniently placed at the side and out of the way of the workman who may be on the ladder.

In case it is desired to place the shelf on the back of the ladder, it may be conveniently attached on the back, as shown in Figs. 2 and 3. The slots in the upper horizontal parts 11 (which previously engage the slots 19 of the bar 14) are made to engage one of the rungs 2. The bar 14 is then inserted between the rod 10 and the bottom 4 and one of its depressions 18 is made to engage the rod 10, whereupon the end of the rod 14 is bent down so that its slot 19 can be made to engage the next lower rung of the ladder, the bar 14 and upper horizontal

parts 11 being thus sprung apart by adjacent rungs 2 of the ladder.

When the angle at which the ladder is inclined is changed, the shelf can be moved to bring its bottom 4 into a horizontal position by disconnecting the bar 14 from the rung 2 and so arranging the bar (with respect to the rod 10), by bringing another depression 18 into engagement with the rod 10 that, when the bar 14 is again connected to the rung 2, the bottom 4 will be held in a horizontal position.

It will be seen further that, to hold the shelf bottom 4 always in a horizontal position, the point of engagement between the bar 14 and rod 10 approaches the end of the bar 14 as the angle at which the ladder inclines from the vertical increases.

What is claimed is:

1. A shelf for ladders comprising substantially Z-shaped hangers, spacing bars connecting the hangers, a shelf attached between the hangers, and a bar having a centrally disposed slot for engagement with the rung of the ladder and end slots adapted to receive the end of the hangers.

2. A ladder shelf, adapted for attachment at the back or sides of a ladder, comprising substantially Z-shaped hangers, a shelf attached between the hangers, a spacing rod attached between the hangers and at a distance below the bottom of the shelf, and a

bar having a centrally disposed slot for engagement with the rung of a ladder, the bar further having two end slots adapted to receive the ends of the hangers and having a series of depressions between the central slot and one of the end slots, whereby the bar may be used as a means for attaching the shelf at the side of or on the back of a ladder.

3. A shelf for ladders comprising Z-shaped hangers, a shelf attached therebetween, and a bar connectible to the ends of the hangers to swing the shelf on the side of a ladder or to support it on the back thereof.

4. A shelf for ladders comprising Z-shaped hangers, a shelf attached therebetween, and a bar connectible to the ends of the hangers to swing the shelf on the side of a ladder or to support it on the back thereof, the bar having means whereby the shelf when supported on the back of the ladder can be made to assume a horizontal position irrespective of the angle of inclination of the ladder.

In testimony whereof I have signed my name to this specification in the presence of two subscribing witnesses.

ARTHUR O'CONNOR.
